(57) **CLAIM**

The ornamental design for an LED illuminating lens as shown and described.

DESCRIPTION

FIG. 1 is a front perspective view of an LED illuminating lens in accordance with a first embodiment showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view taken from an encircled portion 9 of FIG. 1;

FIG. 10 is an enlarged view taken from an encircled portion 10 of FIG. 2;

FIG. 11 is a front perspective view of the LED illuminating lens in accordance with a second embodiment;

FIG. 12 is a rear perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is an enlarged view taken from an encircled portion 19 of FIG. 11; and,

FIG. 20 is an enlarged view taken from an encircled portion 10 of FIG. 12.

The broken lines in the drawings depict portions of the LED illuminating lens that form no part of the claimed design.

1 Claim, 20 Drawing Sheets
